CLAIM

The ornamental design for an electrical connector, as shown and described.

DESCRIPTION

FIG. 1 is a front, right, bottom perspective view of an electrical connector, showing our new design;

FIG. 2 is a rear, left, top perspective view thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a right side view thereof, the left side view being a mirror/inverted image.

The shadings in the figures show contour and not surface ornamentation.

The broken lines in the drawings illustrate portions of the electrical connector that form no part of the claimed design.
